UNITED STATES PATENT OFFICE.

ALFRED HENRY FRANCFT, OF GRANDVIEW-ON-HUDSON, NEW YORK,
ASSIGNOR TO J. B. COLT COMPANY, A CORPORATION OF NEW JERSEY.

ACETYLENE-GAS GENERATOR.

SPECIFICATION forming part of Letters Patent No. 746,811, dated December 15, 1903.

Application filed October 9, 1901. Serial No. 78,050. (No model.)

To all whom it may concern:

Be it known that I, ALFRED HENRY FRANCFT, a citizen of the United States, and a resident of Grandview-on-Hudson, in the county 5 of Rockland and State of New York, have invented certain new and useful Improvements in Acetylene-Generators, of which the following is a specification.

My invention relates to improvements in 10 acetylene-gas generators.

It relates especially to that class of generators known as "wet-process" generators—viz., those in which the carbid is fed into the water in a more or less subdivided state.

15 The object of the invention is to provide a feeding device for handling carbid in all the sizes as manufactured commercially which shall be cheap in construction, simple and efficient in operation, and obviate many of 20 the inconveniences in present generators. I accomplish this object by providing my improved generator with an automatic feed in the shape of a circular drum having an automatically-operating valve, the said drum being mounted eccentrically on its axis.

25 In the drawings, Figure 1 is an elevation, partly in section and showing a small portion of the gasometer; Fig. 2, an elevation, also partially in section, the section being at 30 right angles to that of Fig. 1; Fig. 3, a detail of the manner of admitting the carbid from the hopper into the circular feed; and Fig. 4, a view similar to Fig. 2, showing the operation of feeding the carbid into the water.

35 Referring to the drawings, A is the water-receptacle supplied with liquid by the pipe B; C, the hopper that feeds the carbid into the eccentrically-balanced feeding-drum D.

E is a valve, shown in the shape of a door 40 or shutter, swinging on a pivot F.

G is the axis on which the feeding-drum revolves, having at its outer end a handle H, which is worked by the movements of the bell J of the gasometer K through the inter- 45 mediation of the arm I, attached to the bell.

L is a casing inclosing the drum and directing the carbid into the water, at the same time acting as a seal. The lower portion of the carbid-hopper entering the feeding-drum 50 at an angle, a section through it at its entrance forms an ellipse M. As this would be

an inconvenient shape to feed through when the drum was revolving, the arrangement shown in Fig. 3 is adopted. To the wall of the casing L is fastened a circular metal strip 55 N, which is brought in through a circular opening into the feeding-drum, a space being cut out of one side of the drum D to admit it. This makes a circular opening for the carbid of a diameter about the same as the major 60 axis of the elliptical opening M. To keep the drum away from the casing L and allow it to revolve, a wire O or similar arrangement is attached, as shown in Fig. 3. That the feed of the carbid from the hopper may be perfectly free and no angles presented for collecting carbid, the under side of hopper C is carried in, as shown in Fig. 3.

In order that the vapor of the water may not attack the carbid in the feeding-drum, 70 the valve E is provided with a layer of rubber or similar suitable material Y on its under side, thereby when closed forming practically a moisture-proof joint. This is not an absolute necessity, though preferred, since 75 the drum will feed the same if the valve be not present.

The operation is as follows: Carbid being placed in the hopper, it runs down and fills the receptacle D partially full. The drum 80 being eccentrically balanced, the center of gravity will always be below the point of support G, and this will tend to keep the valve E in its topmost position and closed. When now the gasometer-bell descends and the arm 85 I contacts with the crank H on the axis G, the feeding-drum will be tilted, as shown in Fig. 4, the valve E will open and discharge gradually the carbid into the water. As soon as this takes place gas begins to generate, 90 passes into the gasometer, the bell rises, and the unbalanced weight of carbid immediately acts to bring the valve E to its upper position, and this stops the flow of carbid and closes the valve until such time as the fall 95 of the gasometer-bell repeats the operation. By noticing the amount of arc described by the crank H the amount of carbid in the drum can be determined. If it describes only a small arc, the drum is well filled. If a larger 100 arc, it shows the supply of carbid is getting exhausted. The casing L besides forming

an inclosure for the feeding-drum also serves as a seal. When the carbid has been acted upon by the water, a certain amount of the gas will rise and fill the casing L, forcing down the water in the lower part thereof. If now the hopper be opened, all the gas that can escape is that within the casing, the water then forming a seal.

The advantage of my machine is that I can take commercially-manufactured carbid—that is, carbid varying in size from one-half inch to three inches. This size gives a better yield per pound of carbid than can be attained by those machines limited to a small-sized carbid, the latter being more exposed to the action of the air and deterioration in handling. Other methods of feeding, such as by screws, require breaking up the carbid to a standard size, and such feeds are liable to become clogged. Moreover, such feeds jam and crunch the carbid and cause great inconvenience besides being an element of danger and to a considerable extent exposing the carbid to the action of the water-vapor.

Having thus fully described and illustrated my invention, what I claim is—

1. A feed for acetylene-generators consisting of a hollow carbid-receptacle eccentrically balanced and having an automatically-operating valve for supplying the carbid to the liquid, substantially as set forth.

2. In an acetylene-gas generator the combination of an eccentrically-balanced carbid-receptacle, having an automatic valve, and means for operating the balanced receptacle through the rise and fall of the gasometer-bell, substantially as set forth. 35

3. In an acetylene-gas generator, an eccentrically-hung carbid-feeding device adapted to be actuated in one direction by the weight of the carbid, substantially as set forth. 40

4. In an acetylene-gas generator, an eccentrically-hung carbid-feeding device constructed to be actuated in one direction by the weight of the carbid, and operative connections for actuating the device in the other direction by the movement of the gas-bell, for substantially the purposes set forth. 45

5. In an acetylene-gas generator, an eccentrically-hung carbid-feeding device constructed to be actuated in one direction by the weight of the carbid, and operative connections for actuating the device in the other direction by the descent of the gas-bell, for substantially the purposes set forth. 50

Signed at New York, in the county of New York and State of New York, this 8th day of October, A. D. 1901.

ALFRED HENRY FRANCFORT.
